UNITED STATES PATENT OFFICE.

GEORGE H. WILLIAMSON, OF CHICAGO, ILLINOIS.

DOLL WALKING DEVICE.

1,355,789.

Specification of Letters Patent.

Patented Oct. 12, 1920.

Application filed September 22, 1919. Serial No. 325,284.

To all whom it may concern:

Be it known that I, GEORGE H. WILLIAMSON, a citizen of the United States, and a resident of the city of Chicago, in the county 5 of Cook and State of Illinois, have invented a new and useful Improvement in Doll Walking Devices, of which the following is a full, clear, and exact description.

My invention relates to improvements in 10 doll walking devices, and it consists in the combinations, constructions, and arrangements herein described and claimed.

An object of my invention is to provide a 15 device by means of which a doll may be supported and the feet of the doll caused to reciprocate in a manner which closely simulates walking.

A further object of my invention is to 20 provide a doll walking device having a support, and operative mechanism for actuating the feet or legs of the doll, comprising relatively few parts, these parts being so disposed as to be effectually covered or concealed by the doll's dress when viewed from 25 the front, and to be partially concealed when viewed from the sides.

A further object of my invention is to 30 provide a device which will support the doll in an upright position when left standing, as, for instance, when temporarily abandoned by the child who has been playing with the toy.

A further object of my invention is to 35 provide a device which is relatively simple in construction and of low manufacturing cost.

Other objects and advantages will appear 40 in the following specification, and the novel features of the invention will be particularly pointed out in the appended claims.

My invention is illustrated in the accompanying drawings, forming part of this application, in which—

Figure 1 is a side view of the device as 45 applied to the doll,

Fig. 2 is a section along the line 2—2 of Fig. 1,

Fig. 3 is a section along the line 3—3 of Fig. 1,

Fig. 4 is a section along the line 4—4 of Fig. 1, and

Fig. 5 is a section along the line 5—5 of Fig. 1.

In carrying out my invention, I provide a 55 wheel or roller 1 (see Fig. 2) which is provided with a central groove 2 leaving

a hub portion 3. Looped around the hub portion to form a bearing 4 therefor is a strip of wire whose ends are twisted together, as shown at 5, extend rearwardly and upwardly, and then are bent laterally and downwardly at 6, the end of the wire being looped at 7 to form a slideable foot.

A handle 8 is secured at the end of a pair of twisted wires 9 which extend downwardly, are looped around the wire 5 at 10, and then are bent upwardly, being twisted as shown. One wire 9 terminates at 11 (see Fig. 4), while the other is extended, bent back upon itself at 12 to form a semi-circular support 13, bent again at 14, and is secured to the end of the companion wire 11.

On the opposite faces of the wheel or roller 1 are pins 15 which are connected by links 16 with semi-circular yokes or retaining members 17 formed of small pieces of wire bent in circular form, as clearly shown in the drawings.

From the foregoing description of the various parts of the device, the operation 80 thereof may be readily understood.

The doll 18 is placed against the semi-circular support 13 which extends about the waist and is secured thereto by means of a ribbon 19 which is preferably of a color to 85 match the dress or trimming of the doll. The ankles of the doll are placed in the retaining members 17 and are secured by means of ribbons 20.

Viewing the doll from the front, the supporting members, as well as the means for operating the legs of the doll, are effectually concealed. Now by grasping the handle and pushing the device forwardly, the wheel 1 will rotate and will cause a reciprocation 95 of the legs of the doll in a manner closely simulating a person walking. The members 7 constitute slideable feet or legs to the device, thus obviating the necessity of additional wheels. The device is arranged so 100 that when the doll is secured in position, the toy can be left with the doll standing. It will be observed that the supports are the central wheel 1 and the looped feet 7 which give a three point support.

The device is relatively simple in construction, and is not liable to easily get out of order.

I claim:

1. A doll walking device comprising a 110 wheel having a central peripheral groove, a support formed of a pair of twisted wires,

- one of said wires being extended at the upper end of said support and bent back upon itself to form a semi-circular retaining member, a single piece of wire having its middle portion formed into a bearing disposed within the central peripheral groove of said wheel and having its ends twisted together and bent rearwardly and upwardly to connect with said support, the ends of the wire then diverging and extending downwardly to each form a slideable foot, a yoke arranged to be secured to each leg of the doll, a link pivotally secured to each yoke, the ends of the links being pivotally secured to the opposite faces of the wheel, and means for securing the body of the doll to said semi-circular retaining member.
2. A doll walking device comprising a V-shaped support formed of a pair of twisted wires, one of said wires being extended at the upper end of said support and bent back upon itself to form a semi-circular retaining member, a handle secured to the other end of said V-shaped support for propelling the device, means for securing the body of

the doll to said semi-circular retaining member, a rotatable wheel having a central peripheral groove, a single piece of wire having its looped middle portion disposed within said groove to form a bearing therefor and its ends twisted together and bent rearwardly and upwardly to connect with said V-shaped support, the ends of the wire then diverging and being bent downwardly to each form a slideable foot, a yoke formed of a single piece of wire having a portion of its length formed into an eyelet and another portion of its length bent back upon itself to form a semi-circular retaining member adapted to receive a leg of the doll, means for securing each leg of the doll to one of the last named semi-circular retaining members, a link pivotally secured to the eyelet of each of said yokes, the ends of the links being pivotally secured to the opposite faces of the wheel, whereby the legs of the doll are reciprocated in a manner which closely simulates walking when the wheel is revolved.

GEORGE H. WILLIAMSON.
